R. W. PERRIN,
VENDING MACHINE,
APPLICATION FILED NOV. 9, 1916.

1,269,502.

Patented June 11, 1918.

UNITED STATES PATENT OFFICE.

ROGER W. PERRIN, OF NEW YORK, N. Y., ASSIGNOR TO THEATRE VENDING MACHINE CORPORATION, OF NEW YORK, N. Y., A CORPORATION OF NEW YORK.

VENDING-MACHINE.

1,269,502.

Specification of Letters Patent. Patented June 11, 1918.

Application filed November 9, 1916. Serial No. 130,307.

To all whom it may concern:

Be it known that I, ROGER W. PERRIN, a citizen of the United States, residing at New York, county and State of New York, 5 have invented certain new and useful Improvements in Vending-Machines, of which the following is a full, clear, and exact description.

This invention relates to certain new and 10 useful improvements in vending machines of the type shown and described in my copending applications Ser. Nos. 59,168 and 68,676.

In the latter application a cradle was employed which cradle had upper and lower 15 article engaging pallets. The article was retained upon the lower pallets of the cradle and the falling coin was adapted to trip a detent and permit the cradle to rock to deliver the article. In the present construction 20 the articles in the magazine are retained therein by the upper cradle pallets. Upon the insertion of a coin in the coin slot a member is moved by the coin which rocks the cradle and permits one article to descend to 25 the lower pallets. The cradle is then temporarily retained by the detent until the detent is tripped by the descending coin. The cradle then rocks as before to deliver the article and concurrently therewith the 30 next descending article is retained by the upper pallets swinging into retaining position beneath the article. This construction has proved more satisfactory in practice.

Other detail improvements are made in the 35 coin slot closer and certain other features as will be pointed out in detail hereafter.

Figure 1 shows a front view of a vending machine containing my improvements. The front of the case is shown broken away and 40 certain portions of the inner shell are broken away to show the cradle construction.

Fig. 2 is a sectional view taken on line 2-2 of Fig. 1 and looking in the direction of the arrows.

Fig. 3 shows the position of the cradle at 45 the end of the first step in the operation.

Fig. 4 shows the corresponding position of the detent.

Figs. 5 and 6 show the position of the 50 cradle at the next position with the corresponding detent position. These are the

positions the cradle and detent occupy just before the article is delivered.

Article delivery devices.

55

To retain the articles in the article magazine and to deliver them one at a time to the delivery receptacle at the bottom of the machine, I provide a cradle 35 pivoted in the side walls of an inner shell, and 60 adjacent to the front wall thereof as shown in Fig. 2. The cradle is slightly curved in form and has upwardly extending pallet portions 36 and lower pallet portions 37. The normal position of the cradle is 65 shown in Fig. 2 in which an article 20 rests upon the upper pallets 36. In order that the articles are properly directed onto the pallets I provide camming projections 100 on the inner wall of the case as shown in 70 Fig. 2. The projections direct each cylindrical article to the front of the magazine and facilitate the proper action of the cradle, as will now be explained.

The camming projections 100 direct the 75 cylindrical articles 20^a toward the front wall of the magazine, in order that the weight of the articles may act to the left of the pallets 36, see Fig. 2, and thereby prevent the rocking of the cradle in a clockwise direction. As the counter-clockwise cradle movement is limited, the pallets retain the articles 20^a in the magazine in the position shown. Were the camming projection omitted, the articles might tend to react upon the 85 opposite side of the pallets 36, and rock the cradle clockwise. This action is not desired, hence the camming projections 100.

Upon the insertion of the proper coin in the coin entrance 28, the lower edge of the 90 coin impacts against a turned over end of a vertical bar 102, and as the coin is pressed inward, the bar is forced downward. The bar is suitably guided upon the inner shell and the lower end is slotted to receive a post 95 103 projecting through the wall of the magazine from the cradle. The downward movement of the bar rocks the cradle clockwise to the position shown in Fig. 4. The article held upon the upper pallets 36 descends and 100 is retained upon the lower pallets 37 as shown in Fig. 4. The pivoted gravity acting

detent 40 normally stands in the position shown in Fig. 1, with a second post 45, which is integral with the cradle in engagement with the notch 44. However, as soon as the 5 coin is inserted and the cradle is rocked, the post 45 descends to the position shown in Fig. 3, the detent rocking counter-clockwise to the position shown. Immediately the coin passes by the vertical bar and when the article 10 has impacted upon the lower pallets of the cradle the post 45 will move upward to the position shown in Fig. 5 and engage with the notch 43 in the detent 40.

With the parts in this position the cradle 15 will be held in the position shown in Fig. 6, and the lower pallets 37 will retain an article 20 thereon until the descending coin impacts against the nose of the detent 40 and swings it clockwise about its pivot.

20 When the detent 40 swings clockwise to the position shown in Fig. 1, the post 45 which projects from the cradle will be free to rise into the notch 44. The weight of the article 20 on the lower pallets 37 will rock 25 the cradle counter-clockwise, thereby raising the post into notch 44, swinging back the lower pallets 37 and swinging the upper pallets 36 in the opposite direction to retain the next descending article in the manner 30 shown in Fig. 2. The article 20 which had previously been retained upon the lower cradle pallets is then free to fall to the delivery receptacle at the bottom of the machine.

35 Briefly stated it may be said that the cradle is positively coin operated to swing it from its initial article retaining position to a secondary article retaining position. The cradle is held in this second position 40 by a gravity detent which is tripped by the descending coin to permit the weight of the article on the cradle to act to rock the cradle, deliver the article and retain the next descending article upon the upper cradle pallets.

45 Another feature of the present construction resides in the provision of a coin operated auxiliary detent, which detent co-operates with the cradle controlling detent 50 to prevent the tripping of this latter detent by tapping or hammering the casing of the machine. In practice it has been found that if a coin be inserted in the coin entrance and then withdrawn it sometimes is possible to trip the detent 40 from the position 55 shown in Fig. 5 to that shown in Fig. 1 by hammering or pounding the box. To prevent such tampering I provide an auxiliary detent 115. This detent normally assumes the position shown in Fig. 1. When 60 the coin is inserted in the coin entrance 28 the weight of the auxiliary detent causes it to drop into a notch in the upper part of detent 40. When in this position detent 40 65 is locked against clockwise movement and it

is impossible to release the post 45 from notch 43 until the coin impacts against the auxiliary detent as shown in Fig. 5. Detent 40 is then free to be rocked by the coin as heretofore described.

70 It will also be understood that the auxiliary detent 115 can also be used with the detent shown in my copending application and I desire to here claim broadly the combination of two interacting detents which are 75 tripped by a deposited coin without being limited to the specific mode of operation of the detent herein described.

80 The construction of the case, slug diverter, and kindred parts need not be described in detail here as they have been fully described in the copending applications heretofore referred to. It may be said, however, that any slugs which are diverted from the coin chute by the magnet are prevented from impacting upon the detent 40 by a sloping deflecting plate 33a.

85 The coin slot closer which closes the coin entrance when the machine is empty comprises a pivoted member 110, having a nose 90 111 in proximity to the coin entrance and a tail piece 112, which extends down at the side of the magazine along the side of the articles 20a therein. As soon as the machine is empty, the preponderance of weight of 95 the parts of the pivoted member 110, including tail piece 112 to the left of the pivot, is effective to swing the coin closer counter-clockwise and to project the nose 100 111 into the coin entrance and block it, thereby preventing the insertion of coins in the machine.

105 It will be understood that this invention is not limited to the precise details of construction shown and described but that my invention is susceptible of various modifications which will occur to those skilled in the art. What I claim as my invention is more particularly pointed out in the appended claims.

110 I claim:—

1. In a vending machine, in combination, an article magazine, a rocking cradle which in its normal position lies in the path of the articles tending to issue from 115 the magazine, said cradle being adapted to be rocked from such position by the insertion of a coin and to drop one of the articles from the magazine, into the cradle, means for locking the cradle in its article holding 120 position to which it has been thus rocked, extending into the path of the falling coin so as to be tripped thereby to unlock the cradle, the said cradle when thus freed being adapted to be rocked by the weight of 125 the article contained therein back into its normal position, whereby it will release the contained article and again engage the article above it in the magazine and restrain the latter from issuing therefrom.

2. In a vending machine, in combination, an article magazine, an article retaining cradle therein, means controlled by an inserted coin for rocking the cradle so that it receives from the magazine one of the articles therein, the said cradle being unbalanced when in such position due to the weight of the article which it contains, means for temporarily retaining the cradle in such article holding position, adapted to be tripped by the falling coin to release the cradle, permitting the article thereon to rock said cradle and deliver the article to the purchaser. 10
3. In a vending machine, in combination, an article magazine, a pivoted cradle adapted to receive articles from the magazine when rocked by an inserted coin, and when containing such articles to be overbalanced by the weight of the same, means independent of the cradle rocking means comprising a pivoted detent for automatically engaging and locking the rocked cradle in its article holding position, said detent being adapted to be engaged by the falling coin and to thereby unlock the cradle whereby the weight of the contained article will again rock the cradle to release the article thereon to the purchaser. 15
4. In a vending machine, in combination, with an article magazine, an article retaining cradle having upper and lower pallet portions, said upper pallets being adapted to normally retain the articles in the magazine, coin operated means for rocking the cradle to receive an article on the lower cradle pallets, means for restraining the rocking of the cradle under the influence of the weight of the article, said means adapted to be tripped by the impact of a coin to permit the weight of the article to act and rock the cradle, deliver the article and swing the upper pallets to position to arrest the next descending article in the article magazine. 20
5. In a vending machine, in combination, an article magazine, a cradle adapted to be rocked by means of an inserted coin into a position where it receives an article from the magazine, a detent for locking it in such article holding position, a second detent for engaging with and locking the first named detent against movement, the second detent being adapted to be operated by a falling coin to release the other and thereby unlock the cradle. 25

In testimony whereof I hereunto affix my signature.

ROGER W. PERRIN.
